UNITED STATES PATENT OFFICE.

HARVEY L. EGGLESTON, OF TULARE, CALIFORNIA.

ROAD-DRESSER

1 107,770.

Specification of Letters Patent. Patented Aug. 18, 1914.

Application filed June 23, 1913. Serial No. 775,212.

To all whom it may concern:

Be it known that I, HARVEY L. EGGLESTON, a citizen of the United States, residing at Tulare, in the county of Tulare, State of California, have invented certain new and useful Improvements in Road-Dressers; and I do declare the following to be a full, clear, and exact description of the same, such as will enable others skilled in the art to which it appertains to make and use the same, reference being had to the accompanying drawings, and to the characters of reference marked thereon, which form a part of this application.

15 This invention relates to improvements in road treating implements and particularly to a road dresser adapted to be used to scarify the road, level and roll it, all in one continuous operation.

20 The invention also involves a series of adjustments for the scarifying and leveling means and also a coöperating structure between the two, all for the purpose of permitting the implement to do fine work upon 25 the road surface.

A further object of the invention is to produce a simple and inexpensive device and yet one which will be exceedingly effective for the purposes for which it is designed.

30 These objects, I accomplish by means of such structure and relative arrangement of the parts as will fully appear by a perusal of the following specification and claim.

On the drawings, similar characters of 35 reference indicate corresponding parts in the several views.

Figure 1 is a side elevation of the complete device. Fig. 2 is a top plan view of the same. Fig. 3 is a detached view of a 40 spring adjustment means. Fig. 4 is a fragmentary view of a swiveled bearing for a spring adjustment means.

45 Referring now more particularly to the characters of reference on the drawings, the numeral 1 designates the main suspending beams for the platforms of the device, such beams each being provided with a front platform 2 and a rear platform 3 or such other platforms as may be desired. The forward part of the members 1 are suspended upon wheels 4 being suitably provided with a fifth wheel or other similar turning mechanism 5. The rear end of the device is suitably supported by brackets 6 mounted 50 on a roller 7 of suitable size and weight to

roll the road surface after it has been scarified and leveled as will appear.

The numeral 8 designates a scarifying device of the type shown in my Patent No. 969,850 and dated September 13th, 1910, 60 hence no specific description of the same will be here entered into. In my improved device this scarifier is suspended on four upright members 9 provided with gear racks 10 engaging gears 11 on shafts 12, 65 each shaft having a pinion 13 engaging a worm gear on a horizontal shaft 15 provided with an operating wheel 16 disposed within reach of a seat 17 on the rear platform 3 or at other suitable location. Hence, by the 70 operation of the wheel 16, the scarifying device may be raised or lowered to adjust it at the proper height to do the desired quality of work. In order to permit the scarifier to compensate for unusual unevenness in the road surface, I provide the following resilient means, namely: On the lower ends of the members 9 are pins 18 projecting in a movable manner through plates 19 secured to the scarifier, said pins having 75 heads 20 engaging the underside of said plates 19 to suspend said plates and incidentally the scarifier thereon. At a spaced distance from the plates 19 I provide collars 21 and interpose springs 22 between said 80 collars 21 and said plates 19. By means of this structure, the scarifier may move slightly up and down on the pins 18 against the resistance of the springs 22 which will allow them to ride over unusual rough 85 places in the road and then resume their normal position with the tension of the springs 22.

Hinged to the rear of the scarifier 8 is a frame 23 pivotally mounted on which, as 90 at 24, is a downwardly projecting leveling beam 25 extending from side to side of the frame 23. This beam 25 is provided with a quadrant 26 having an adjustment wheel operated set screw 27 whereby the beam 25 100 may be turned to any angle desired and then fixed in that position by means of the wheel 27. The frame 23 and incidentally the beam 25 is adjustable vertically by means of a pin 27* connected therewith and projecting 105 through a swiveled bearing 28 and provided on its upper end with an operating wheel 29, said pin 27* being threaded at 30 to be screw mounted through the bearing 28. The member 27* has at its lower end, as at 31, 110

a connection similar to the connection 18 to 22 on the members 9 and for a similar function. The purpose of the swiveled bearing 28 is to compensate for the hinged swinging 5 movement of the frame 23 on the scarifier 8.

In operation the scarifier 8 scarifies the road, the level beam 25 levels it and the roller 26 rolls it, all in one continuous operation from which it will be apparent that 10 the implement provides a very efficient means for the treatment of road surfaces.

The numeral 32 designates hinged scrapers bearing against the top of the roller 7 and held in such position by weights 33 15 for the purpose of keeping the roller free of dirt, mud, etc.

From the foregoing description it will be readily seen that I have produced such a device as substantially fulfills the objects of 20 the invention as set forth herein.

While this specification sets forth in detail the present and preferred construction of the device, still in practice, such devia-

tions from such detail may be resorted to as do not form a departure from the spirit 25 of the invention.

Having thus described my invention what I claim as new and useful and desire to secure by Letters Patent is:—

The combination with a wheel mounted 30 frame having a scarifier and a roller mounted thereon in spaced relation, of a leveling frame disposed between said scarifier and said roller and hinged to said scarifier, a bearing swivelly mounted on said wheel 35 mounted frame, a vertical rod screw mounted through said bearing and connected with said leveling frame, and an operating wheel on said rod, as described.

In testimony whereof I affix my signature 40 in presence of two witnesses.

HARVEY L. EGGLESTON.
